UNITED STATES PATENT OFFICE.

HARRISON GARNETT, OF NORRISTOWN, PENNSYLVANIA.

MEASURING AND MARKING DEVICE FOR BEAMING FRAMES FOR LOOMS.

Original application filed September 14, 1921, Serial No. 500,518. Patent No. 1,431,449. Divided and this application filed August 21, 1922. Serial No. 583,458.

To all whom it may concern:

Be it known that I, HARRISON GARNETT, a citizen of the United States, residing at Norristown, in the county of Montgomery, and State of Pennsylvania, have invented a new and useful Improved Measuring and Marking Device for Beaming Frames for Looms, of which the following is a specification.

10 My invention relates to devices used for automatically measuring and marking off certain lengths of yarn or warp as it is wound onto a loom beam from a reel or other source. The length marks may be 15 made on the warp at required or predetermined distances for instance every forty, sixty or any other number of yards.

While my improved measuring device may be used in connection with all kinds of 20 beaming frames or other similar machines, yet it is especially adapted to be used in connection with "the combined beaming frame and press for looms" for which an application for U. S. patent was filed September 14, 1921, under Serial #500518, of which this application is a division.

My invention consists of the combination of a drum having a certain diameter and upon which the beam receiving the warp is 30 loosely mounted or pressed, and mechanism operated from the drum shaft to actuate a chalk-cup at predetermined intervals.

My invention will be more fully understood taken in connection with the accompanying drawings in which:

Fig. 1 is an elevation of a part of a beaming frame and showing the measuring device applied thereto, and

Fig. 2 is an end view of Fig. 1.

40 Referring now to the drawings for a further description of my invention, D is a drum of wood or other suitable material and having a shaft d fastened to the drum; the shaft is journalled in standards and is 45 driven by suitable gearing not shown. On top of the drum is loosely mounted in slotted bearings b³ the beam B, and this beam receives the yarn from a reel not shown, in the usual or any preferred manner, and in 50 its travel it passes over the rod or shaft e.

On the drum shaft d is secured a cross-head m, in which one adjustable pin m¹ is secured, to oscillate the lever m², hinged at m³ and held back by the spring m⁴. At the 55 upper end of the lever m² is adjustably se-

cured a pawl m⁵, which engages a ratchet wheel m⁶ having a number of teeth. A pin m⁷ in the face of the wheel m⁶ is provided to trip a lever m⁸ once at every revolution; and this lever fulcrumed in a slotted connection at m⁹ has a chalk cup m¹⁰, which may be raised or lowered by turning the two nuts m¹¹. Whenever the lever m⁸ is tripped, the chalk-cup m¹⁰ is thrown up against the passing warp and leaves a mark on said warp.

The operation of my device is as follows: The drum is preferably made to measure two yards in its circumference and therefore as it makes one complete revolution two yards of yarn have passed from the reel 70 onto the beam B. The crosshead m shown in Fig. 2 is provided with only one pin m¹, and the lever m² with pawl m⁵ is therefore actuated only once at every revolution of the drum D, if now the ratchet wheel m⁶ 75 has forty teeth then the pin m⁷ will trip the lever m⁸ once in forty revolutions of the drum or after 80 yards of yarn have been wound onto the beam B. If the passing warp is to be marked every 40 yards another pin m¹ is inserted in the crosshead m or another pin m⁷ in the face of the wheel m⁶; and if any other number of yards are to be marked off, another wheel with the required number of teeth is used as will be 80 readily understood.

It will be understood by those skilled in the art that modifications may be made in the arrangement and use of other mechanism without departing from the spirit of the invention, and having thus fully described the nature and objects of my invention what I claim as new and desire to secure by Letters Patent is:

1. In combination with a beaming frame 95 for looms having a drum, a measuring and marking device comprising a ratchet wheel journalled on a stud of the frame, a lever with chalk-cup adjustably pivoted also to the frame, a pin or projection on said ratchet wheel to trip said lever, and means to rotate said ratchet from the shaft of said drum, substantially as and for the purpose set forth.

2. In combination with a beaming frame 100 for looms having a drum, a shaft for said drum, a cross-head on said shaft, an adjustable pin in said cross-head, a lever fulcrumed with one end to a fixed support, a pawl on the other end of said lever, a spring 110

to hold the lever towards the said pin, a ratchet wheel pivoted to a support and actuated by said pawl, a pin in one face of the ratchet wheel, and a tilting lever having a marking cup and operated by said pin at each rotation of said ratchet wheel, substantially as and for the purposes set forth.

3. In combination with a beaming frame for looms having a drum, a shaft fixed to 10 and rotating with said drum, a beam to receive the warp and resting on said drum, a measuring device for said warp consisting of a tilting lever adjustably hinged to a support, a chalk-cup on one end of said tilting 15 lever, a ratchet wheel journalled on a fixed

support, a pin on said ratchet wheel adapted to engage the other end of said tilting lever to force the chalk cup up against the warp and leave a mark on said warp, and means to operate the ratchet wheel from the 20 said drum shaft, substantially as and for the purpose set forth.

In witness whereof I have hereunto set my hand in the presence of two subscribing witnesses.

HARRISON GARNETT.
